PAGE 4

FIG. 5

FIG. 6

FIG. 8

FIG. 7

FIG. 1 is a front perspective view of a telephone booth showing our new design;

FIG. 2 is a rear perspective view of the booth shown in FIG. 1;

FIG. 3 is a sectional view of the lower portion of the booth shown in FIG. 1;

FIG. 4 is a front perspective view of another embodiment of the invention shown in FIG. 1;

FIG. 5 is a rear perspective view of the booth shown in FIG. 4;

FIG. 6 is a sectional view of the lower portion of the booth shown in FIGS. 4 and 5;

FIG. 7 is a front perspective view of another embodiment of the invention shown in FIG. 1, and

FIG. 8 is a sectional view of the lower portion of the booth shown in FIG. 7.

We claim:

The ornamental design for a telephone booth, as shown and described.
